UNITED STATES PATENT OFFICE

FRANK H. WAITE AND GEORGE W. DAVEY, OF LONG ISLAND CITY, NEW YORK

FURNACE CONSTRUCTION

Application filed November 13, 1925. Serial No. 68,878.

Our invention relates to furnace construction, and contemplates the provision of simple and efficient means for preheating air for combustion and delivering it to the furnace, while at the same time protecting the refractories. By our construction there are a plurality of co-operating although separate and distinct circulations of air employed in addition to the air supplied by a blower in the usual way, two of the circulations being directed throughout the side walls into the combustion chamber and a third circulation throughout the air cooled arch entering the throat of the furnace.

15 This is accomplished by utilizing the heat transfer function of our air cooled refractory furnace blocks, specifically illustrated, described and claimed in our application bearing Serial Number 55,752, filed September 20 11th, 1925.

We also utilize the horizontal and vertical expansion means illustrated, described and claimed in our pending applications, filed September 29th, 1925, bearing Serial Number 59,440 and in the application filed October 15th, 1925, bearing Serial Number 62,630.

One object of our invention is to circulate air under pressure throughout the side walls of a stoker furnace and force the preheated air into the combustion chamber adjacent to the stoker grate and simultaneously circulate air through an air cooled arch.

Another object of our invention is to circulate air under pressure throughout the side walls of a stoker furnace by the suction of a blower or fan and force this preheated air under the grate of a stoker into and throughout the combustion chamber, simultaneously forcing air throughout an arch into the throat of the said furnace.

Other valuable features of our invention and the unique applications of the circulations are described, pointed out and illustrated in the accompanying drawings, wherein like numerals indicate like parts, in which:—

Figure 1 is a longitudinal section of a water tube boiler stoker furnace.

50 Figure 2 is a cross section on the line 2—2 of Figure 1.

Figure 3 is a typical section of part of the wall adjacent to the grate and taken on the line 3—3 of Fig. 1.

Figure 4 is a longitudinal section of a water tube boiler stoker furnace illustrating a modification.

Figure 5 is a cross section on the line 5—5 of Figure 4.

Figure 6 is a partial horizontal section on line 6—6 of Figure 1.

Figure 7 is a partial horizontal section on line 7—7 of Figure 4.

Figures 1, 2, 3 and 6 illustrate a water tube boiler stoker furnace consisting of a front wall 1, side walls 2 and 3, bridge wall 4, water tubes 5, a drum 6, an angular baffle 7, a vertical baffle 8, a gas outlet 9, a clean out opening 10, a grate 11, a combustion chamber 12, a stoker mechanism 13, a coal hopper 14, a blower or fan 15, a wind box 16 and an arch 17.

There are four separate and distinct circulations of air throughout the walls, arch and the furnace, illustrated in Figures 1, 2, 3 and 6, two of which circulate under the pressure of a fan or blower throughout the side walls, cooling the interior of the furnace or that portion of the furnace built up of a series of superimposed, broken jointed air cooled refractory blocks and the air preheated in transit throughout said walls is utilized as preheated air at a part adjacent to the grate, for a more perfect combustion of the fuel.

In the third circulation the air from the blower is forced throughout the air cooled refractory blocks of an arch and injected into the furnace above the arch or into the throat of the furnace.

In the fourth circulation, illustrated in Figures 1, 2, 3 and 6, the air from the blower enters the wind box, passes under the stoker grate, through an elbow provided with a regulating damper, flows upwardly through the grate and fuel bed into the combustion chamber, through the throat around the tubes, drum and baffles to the gas outlet and stack.

In the first circulation throughout wall 3, illustrated in Figures 1, 2, 3 and 6, the air from the blower 15 driven by the motor 19 100

and belt 18 passes through a pipe or conduit 27 into the wind box 16, from whence it flows into the duct 22 provided with a volumetrically controllable damper 67 within the wall 3, enters the duct 23, flows horizontally at right angles to the flow of flaming gasses within the combustion chamber 12, throughout the wall 3 (which is provided with horizontal baffles 28 and 29, vertical expansion 10 means 30, horizontal expansion means 31 and 32), thence downwardly and then laterally through interstices 33 in the brick work of the wall under the air cooled refractory blocks 24, adjacent to the grate 11, into the combustion 15 chamber 12, as clearly shown in Figures 1, 2, 3 and 6.

The wall 3 as well as the wall 2 is built up of a series of superimposed, broken jointed air cooled refractory blocks 24, illustrated in 20 Figures 2 and 6.

In the second circulation, throughout wall 2, illustrated by Figures 2, 3 and 6, the air from the blower 15, driven by the motor 19 and belt 18, passes through the pipe or conduit 27, into the wind box 16, from whence it flows into the duct 34 provided with a volumetrically controllable damper 68, within the wall 2, enters the duct 35, flows in a horizontal direction throughout the wall 2, directed by the horizontal baffles 36 and 37, flowing at right angles to the flow of flaming gases within the combustion chamber 12, and finally enters the combustion chamber 12 at a point adjacent to the grate 11 through the 35 interstices 33^a in the brick work constituting part of the wall 2 and supporting the air cooled blocks 24.

In the third circulation illustrated in Figures 1, 2, 3 and 6, the air from the blower 15 40 passes into the conduit or pipe 27, enters the conduit or pipe 38 flowing upwardly into the manifold 40 through the elbow 39, the volume of air being controlled or regulated by the damper 54 in pipe or conduit 38.

45 From this manifold 40, the air under pressure of the blower 15 passes throughout the arc 17 which is made up of a series of unit blocks 53, each having a flue 41 therein, into another manifold 42, common to all the flues 50 41, from whence it passes, preheated, after cooling the arch in transit therethrough, into another manifold 44, through the flue 43.

The preheated air thus collected by the manifold 44 is directed into the throat 46 of 55 the furnace by a multiplicity of flues, ducts or passages 45.

In the fourth circulation as illustrated by Figures 1, 2, 3 and 6, the air from the blower or fan 15 passes into the wind box 16 through 60 the conduit or flue 27, under the grate 11, through the elbow 20, provided with a damper, valve or equivalent 21 controlling the volume of air from the wind box 16.

The air thus forced under the grate 11 65 passes upwardly through the grate and fuel

thereon, into the combustion chamber 12, upwardly through the throat 46, around tubes 5, and drum 6, over baffle 7, downwardly around tubes 5 under baffle 8, upwardly around tubes 5 and drum 6 to gas outlet 9 70 from whence it goes to the stack.

Figures 4, 5 and 7 illustrate modified circulations of air as applied to a water tube boiler stoker furnace, one circulation passing throughout one side wall to the inlet side of the blower, one circulation passing throughout the other side wall to the inlet side of the blower, the third passing from the blower throughout the arch into the throat of the furnace while the first and second circulations pass through the blower and throughout the furnace as hereinafter more fully described. 75

The greater part of the air the blower sucks in, preheated in transit throughout each side wall is forced under the grate into the combustion chamber throughout the furnace, while the lesser part is forced throughout the arch into the throat of the furnace. 80

In the first circulation illustrated by Figures 4, 5, and 7, the air enters the side wall 3, composed of a series of superimposed, broken jointed air cooled refractory blocks 24, having horizontal flue 25 and vertical flues 26 therein, through a multiplicity of flues each provided with a damper 69 and slide 70 into the upper horizontal flue, passes downwardly in a direction opposite to the flow of flaming gases within the combustion chamber 12, into a common manifold 57, from whence the air preheated in transit throughout the wall 3 90 enters the inlet side of the blower 15 being directed by the conduits 58, 59 and 60, elbows 61, 62 and 63 and T 65, the greater part of the air from the wall 3 thus preheated being forced through the duct 27 into the wind box 16, through the elbow 20, provided with a volumetrically regulatable damper 21, under the grate 11, upwardly into the combustion chamber 12, through the throat 46, upwardly around the tubes 5 and drum 6, over baffle 7, 100 downwardly around tubes 6 under baffle 8, upwardly around tubes 5 and drum 6 through the gas outlet 9, to the stack. 110

In the second circulation illustrated in Figures 4, 5 and 7, the air enters the side wall 2, of similar construction as hereinbefore described for wall 3, through a multiplicity of ducts, flues, or openings 56, each provided with a damper 69 and slide 70 into the upper horizontal flue, passes downwardly in a direction opposite to the flow of flaming gases within the combustion chamber 12, into a manifold 66, through elbow 64, conduit 58, T 65, conduit 59, elbow 62, conduit 60, elbow 63 to the inlet side of the blower 15, from whence a greater part of this air preheated in transit throughout the air cooled refractory blocks in wall 2, is forced by the blower 15 into the wind box 16 through the conduit or flue 27, under the grate 11, through the elbow 120 125 130

20, provided with a volumetrically regulatable damper 21, passes upwardly into the combustion chamber 12, through the throat 46 around the tubes 5 and drum 6, over baffles 7, 5 downwardly around tubes 5, under baffle 8, upwardly around tubes 5 and drum 6, through the gas inlet 9 to the stack.

In the third circulation a portion of the air from the blower 15, which is sucked in and 10 throughout the walls 2 and 3 is forced upwardly in the conduit 38, having a volumetrically controllable damper 54, through elbow 39, into manifold 40, throughout the arch 17, composed of a series of unit air cooled refractory blocks each having a flue 41 therein, to a manifold 42, which like manifold 40 is common to all the flues 41, from whence the air preheated in transit is directed to manifold 44 through the duct 43, from whence the 20 air is directed into the throat 46 of the furnace through a multiplicity of ducts, flues or passages 45.

This preheated air passes upwardly around tubes 5 and drum 6, over baffles 7, downwardly around tubes 6 under baffle 8, upwardly around tube 5 and drum 6 out of the gas outlet 9 to the stack.

In Figures 1, 2, 3, 4, 5, 6 and 7 the preheated air from the walls is utilized for a more complete combustion of the products of combustion in the combustion chamber and the preheated air for the arch is utilized in the throat of the furnace above the combustion chamber.

Having thus described and illustrated the 25 preferred embodiment of our invention we do not desire to limit ourselves to the exact subject matter pertaining to the specific circulations and combinations thereof disclosed herein, as modifications may be made without departing from the spirit of the invention or 40 the scope of the claims.

We claim:

1. A furnace construction comprising, in combination, channelled refractory walls and 45 a channelled refractory roof forming a combustion chamber, means for admitting fuel to the chamber, an offtake therefrom, a forced draft creating means, air inlet means and outlet means for the channel system of said roof, 50 separate air inlet and outlet means for said wall channels, direct air delivery means from said drafter to said chamber, and means connecting said roof and wall channel systems with said drafter forming indirect air delivery means whereby air from the inlets is forced through said systems, for preheating it and cooling the refractories, and by way of 55 said outlets to the chamber, the air from said roof system being delivered adjacent the offtake, and the other air being delivered adjacent the center of combustion.

70 roof, separate air inlet and outlet means for said wall channels, direct air delivery means from said drafter to said chamber, and means connecting said roof and wall channel systems with said drafter forming indirect air delivery means whereby air from the inlets is forced through said systems, for preheating it and cooling the refractories, and by way of 75 said outlets to the chamber, together with independent air control valves for the direct delivery means and the channel systems.

3. A furnace construction comprising, in combination, channelled refractory walls and a channelled refractory roof forming a combustion chamber, means for admitting fuel to the chamber, an offtake therefrom, a forced draft creating means, air inlet means and outlet means for the channel system of said roof, 80 separate air inlet and outlet means for said wall channels, direct air delivery means from said drafter to said chamber, and means connecting said roof and wall channel systems with said drafter forming indirect air delivery means whereby air from the inlets is forced through said systems, for preheating it and cooling the refractories, and by way of 85 said outlets to the chamber, together with independent air control valves for the direct delivery means and for each of the channel systems.

4. A furnace construction comprising, in combination, channelled refractory walls and a channelled refractory roof forming a combustion chamber, means for admitting fuel to the chamber, an offtake therefrom, a forced draft creating means, air inlet means and outlet means for the channel system of said roof, 90 separate air inlet and outlet means for said wall channels, direct air delivery means from said drafter to said chamber, and means connecting said roof and wall channel systems with said drafter forming indirect air delivery means whereby air from the inlets is forced through said systems, for preheating it and cooling the refractories, and by way of 95 said outlets to the chamber, together with independent air control valves for the direct delivery means and for each of the channel systems.

4. A furnace construction comprising, in combination, channelled refractory walls and a channelled refractory roof forming a combustion chamber, means for admitting fuel to the chamber, an offtake therefrom, a forced draft creating means, air inlet means and outlet means for the channel system of said roof, 100 separate air inlet and outlet means for said wall channels, direct air delivery means from said drafter to said chamber, and means connecting said roof and wall channel systems with said drafter forming indirect air delivery means whereby air from the inlets is forced through said systems, for preheating it and cooling the refractories, and by way of 105 said outlets to the chamber, the air from said roof system being delivered adjacent the offtake, and the other air being delivered adjacent the center of combustion.

Signed at Long Island City, in the county 115 of Queens and State of New York, this 12th day of November, A. D. 1925.
